UNITED STATES PATENT OFFICE.

BYERS W. KADEL, OF BALTIMORE, MARYLAND, ASSIGNOR TO THE SYMINGTON COMPANY, OF NEW YORK, N. Y., A CORPORATION OF MARYLAND.

DRAFT RIGGING.

Application filed September 16, 1925. Serial No. 56,760.

The invention relates to draft rigging, and more particularly to a connection between the draft lugs, coupler and yoke.

The principal object of my invention, generally considered, is the modification of the length of the slots in cooperating draft lugs, couplers and yokes, whereby certain important advantages are obtained.

An object of my invention is the construction of a connection between a coupler, yoke and associated draft lugs and the relative length of the slots therethrough, whereby an associated draft key serves to support said coupler and yoke in operative position, 15 said draft lug slots being materially decreased in length for the purpose of providing an extra strong inner abutment for the associated key as well as forming a front follower abutment of unusual strength, the 20 decreased motion of the key in said draft lug slots being compensated for by providing a slot through the coupler with a correspondingly increased length, whereby normal travel of the coupler is permitted.

Another object of my invention is the decrease in length of the draft key slots through the yokes, and particularly through yokes of the vertical type, in which said slots are formed in substantially vertical 25 spaced webs connecting the forward portions of the arms thereof, whereby the draft key abutments at the inner ends of said slots are correspondingly increased and strengthened, the normal travel of the associated 30 couplers being permitted and provided for by correspondingly increasing the length of the draft key slots therein.

A further object of my invention is the formation of the follower abutments on rail-way draft lugs, particularly those of the A. R. A. type, of increased depth or length, the outer ends of said abutments serving as draft key abutments and extending toward each other for substantially the full width of 45 the follower abutments, whereby the draft key span is proportionately decreased, permitting said draft key to carry a correspondingly greater buffing force.

A still further object of my invention is 50 the provision of a connection between a slotted coupler and a slotted yoke supported from slotted draft lugs by an associated key

extending through the slots in said members, the lengths of said slots being so proportioned that travel of the key is materially less than the travel of the coupler when moving in one direction, and more particularly in a rearward or buff transmitting direction, such a construction making it permissible to increase the strength of the key 55 and follower abutments on the draft lugs as well as the key abutments on the yoke.

There are other objects and advantages of my invention which will become more apparent as the description proceeds.

Referring to the drawings illustrating my invention, the scope whereof is defined by the claims:

Figure 1 is a plan view partly in horizontal section on the line 1—1 of Figure 2, 70 illustrating an embodiment of my invention.

Figure 2 is an elevational view shown partly in vertical section on the line 2—2 of Figure 1.

Figures 3 and 4 are views, similar to Figures 1 and 2 respectively, showing a modification.

Referring to the drawings in detail, like parts being designated by like reference characters, and first considering Figures 1 and 2, there are shown front draft lugs 1 connected to the draft or center sills 2 on the inner faces of the webs 3 thereof by means of a plurality of rivets 4. Said lugs 1 are provided with follower and draft key 80 abutment portions 5 extending toward each other, the inner or rear faces of said abutment portions serving for operatively engaging a front follower 6 associated with cushioning mechanism 7, of any desired 85 type. The outer or front face of the abutment portions 5 define the rear or inner ends of the slots 8 through said draft lugs. Said slots 8 are materially shortened, whereby the longitudinal dimension or depth of said abutment portions 5 is materially increased 90 with the draft key abutment face continued for substantially the full width of the follower abutment face, thereby materially decreasing the span or beam length of the 95 associated draft key 9 which, as illustrated, engages said draft lugs in the slotted portions 8 thereof.

Said draft key 9, in accordance with the

usual practice, serves for supporting, in operative relation, a coupler 10 and associated yoke 11. The rear or inner end of the coupler 10 engages the front face of the follower 6, in accordance with the usual practice. In the embodiment illustrated, although I do not wish to be limited to such a showing, the yoke is of the vertical type with forwardly extending arms 12 and 13 from a rear U-shaped portion (not shown), the forward ends of said arms being connected by slotted webs or substantially vertical wall portions 14 and 15.

To compensate for the restricted travel between the key 9 and the draft lugs 1, because of the decreased length of the slots 8 through said draft lugs, so that a normal amount of travel of the coupler 10 is permitted, the slot 16 in said coupler, through which the draft key 9 extends, is formed of a length materially greater than normal, said increase in length preferably corresponding to the decrease in length of the slots 8 in the draft lugs 1. As will be apparent from a consideration of the drawings, the slot 16 is extended in length outwardly, in accordance with the decrease in length of the slots 8 in the draft lugs 1 forwardly, so that normally there is only relative movement between the coupler and draft key when buffing forces act on said coupler. To correspond with the decrease in length of the slots 8 in the draft lugs 1, the slots 17 and 18, through the walls or webs 14 and 15, respectively, of the yoke 11 are preferably correspondingly shortened, thereby making it possible to effect a material increase in length of the rear key-abutment portions 19 and 20 on said yoke, and particularly the webs 14 and 15 thereof.

From a consideration of the foregoing, it will be apparent that when in operation there is no change in the action of the draft gear on account of my improved construction when draft forces are applied to the coupler. When, however, buffing forces are applied to said coupler there is a materially different action in that the coupler first moves with respect to said draft key 9 until the outer draft key abutment at the outer end of the slot 16 therein engages the outer edge of the draft key 9 and carries said key rearwardly to eventually abut against the draft key and front follower abutment portions 5 of the draft lugs 1. When this has been effected, it will be apparent from the foregoing, a full amount of coupler travel has been permitted and the cushioning mechanism 7 will have been compressed to its full capacity. The engagement between the draft key 9 and the abutment portions 5 then effects a transfer of buffing forces directly from said key to the draft lugs 1 and associated draft sills 2. By reason of the relatively small and decreased span provided,

the draft key is able to transmit such forces to a materially greater degree than normally.

On account of the coupler not immediately engaging and carrying with it the key 9, a reduced travel of said key results with a consequent decrease in wear thereof. On account of the increased length of the abutment portions 5 of the draft lugs 1, a great improvement in effective strength of the draft lugs 1 is secured without increasing the overall dimensions and without materially increasing the weight of said lugs. A similar increase in strength is effected adjacent the draft key abutments 19 and 20 on the yoke 11. By reason of the coupler not engaging with the key immediately upon the application of buffing forces to said coupler, the cushioning mechanism will be stressed to a material extent and the speed of the coupler decreased almost to a standstill before the key is picked up or engaged thereby. On account of this action the force transmitted from the coupler to the key and the corresponding force transmitted from the key to the draft lugs upon travel of the key to the corresponding or inner ends of the slots in said draft lugs is practically merely a static force rather than a dynamic force and the resulting strain on the affected parts is thereby materially decreased.

Referring now to the embodiment of my invention illustrated in Figures 3 and 4, a construction is there shown utilizing a coupler with a standard slot therein as well as a standard yoke, cooperating with draft lugs, embodying features of my invention. According to this modified construction, the key 9^a is received in the slot 16^a in the coupler 10^a with only the normal amount of clearance. The slots 8^a in the draft lugs, however, are of decreased length, as in the embodiment of my invention illustrated in Figures 1 and 2, whereby the abutments 5^a are of corresponding increased strength. In order to provide for normal travel of the coupler, it is necessary, in this instance, to cut away the ends of the key 9^a, as indicated at 21 and 22, an amount corresponding to the decrease in length of the slots 8^a in the draft lugs so that a normal amount of travel is allowed between the key 9^a and the draft lugs 1^a. The portions cut away at 21 and 22 need only extend inwardly or toward the center of the key far enough to clear the inner edges of the abutment portions 5^a of the draft lugs 1^a if said key is employed with a yoke 11^a of the standard type or one with slots 17^a and 18^a therethrough of normal length, as is illustrated in this modification. If, however, a yoke with shortened slots and strengthened abutment portions at the inner ends of said slots is employed, as in the first embodiment of my invention, it is necessary to extend the cut away portions 21 and 22 inwardly so as to clear said key abutment 130

portions of the yoke in the same manner in which the abutment portions 5^a of the draft lugs 1^a are now cleared.

On account of the relatively small transverse clearances between the coupler, yoke and draft lugs, it is preferable, in the present instance, to center the key 9^a with respect to the coupler 10^a by any usual or desired means. In the present instance, a vertical pin 23 is shown extending through the coupler and intersecting the draft key or an edge thereof for centering said key therein or preventing relative transverse motion therebetween. Said centering device 23 may 10 be provided with a head 24 for limiting the downward movement thereof and with retaining means through the lower end of said pin such as, for example, the cotter 25.

In this second embodiment of my invention, heretofore described, certain advantages are secured and disadvantages incurred with respect to the first embodiment disclosed. For example, in the second embodiment, it is possible to employ standard couplers and yokes merely utilizing reinforced draft lugs, in accordance with my invention, and modifying the associated key member by decreasing the slot engaging ends thereof to correspond with the decreased length of said slots. Although, on account of cutting away portions of the key, said key is decreased in strength, yet said decrease is at the ends of the key where the metal is not ordinarily stressed 25 as much as in the center thereof so that said key will still be amply strong for the desired purpose. Because, in this second embodiment, the key travels the same distance that the coupler does, certain of the advantages mentioned in connection with the relative movement between coupler and key, as in the first embodiment of my invention, are missing, as will be understood.

Having thus described the invention, I claim:

1. The combination with a slotted coupler, of slotted draft lugs connected to the inner faces of the draft sills, a slotted yoke, the slots in said draft lugs being of such length as to limit the travel of the coupler key to less than the travel of the coupler, those portions of said lugs adjacent the rear ends of said slots being materially reinforced by relatively thick metal which is extended for substantially the full width of said lugs to engage the key therealong and reduce the effective beam length thereof, the slot in the coupler normally engaging one edge of the key and spaced from the opposite edge thereof, whereby the coupler and yoke move as a unit in one direction and have relative movement in the opposite direction.

2. In a railway draft rigging, in combination with draft sills, of slotted draft lugs connected thereto, a slotted coupler, a slotted

yoke, a draft key extending through the slots in draft lugs, coupler and yoke for holding said coupler and yoke in operative relation, those portions of said lugs adjacent the rear ends of the slots therein being 70 extended into corresponding slots in the draft sills and materially thickened toward the key and extended for substantially the full width of the lugs thereby increasing the effective strength of said key, the slot 75 in the coupler being abnormally long and those in the yoke and lugs abnormally short whereby the key travels less than the coupler on buff.

3. In a railway draft rigging, in combination with draft sills, of slotted draft lugs connected thereto, said lugs having abutment portions adapted for engagement with a co-operating front follower member, said abutment portions being reinforced by discontinuing the slots at a greater distance than normal from said abutment portions to leave a larger amount of metal therein, a slotted coupler, a slotted yoke, a draft key extending through the slots in draft lugs, coupler and yoke for operatively supporting said coupler and yoke, the reinforcement of said abutment portions adjacent the rear ends of the slots being continued for substantially the full width thereof whereby not only is 95 the strength of the abutments increased but the bearing area for the key is likewise increased, the slot in the coupler permitting movement with respect to the key in one direction and moving the key with it in the other direction, and the slots in the yoke being correspondingly shortened.

4. In a railway draft rigging, in combination with draft sills, of draft lugs connected to the inner faces thereof, said lugs being provided with front follower abutment portions with the slots through said lugs decreased in length for correspondingly increasing the strength of said abutment portions, a slotted coupler, a slotted yoke, a draft key extending through the slots in draft lugs, coupler and yoke for holding said coupler and yoke in operative relation, said abutment portions being increased in strength by extending the metal for substantially the full width of the abutments to the rear ends of the key slots thereby increasing the effective strength of said key against buffing forces, the slot in the coupler being of a length greater than normal corresponding to the decrease in length of the draft lug slots for permitting relative motion between the coupler and draft key, corresponding to the decreased motion between the draft key and draft lugs, and the slots in the yoke being decreased in length in accordance with the decrease in length of the draft lug slots.

5. In a railway draft rigging, in combination with draft sills, of slotted draft lugs

connected thereto, a slotted coupler, a yoke in which the slots thereof are decreased in length to reinforce the rear walls thereof, a draft key extending through the slots in draft lugs, coupler and yoke for operatively supporting said coupler and yoke, said draft lugs being provided with abutment portions extending inwardly to not only engage an associated front follower but also engage 10 the key along substantially the full width of said portions, the slot in the coupler being lengthened to correspond with the shortening of the slot in the yoke, whereby a normal amount of travel therebetween is 15 permitted.

6. In a railway draft rigging, in combination with draft sills and slotted draft lugs connected thereto, a slotted coupler, a yoke provided with slots materially shortened for 20 reinforcing the inner ends of the yoke webs through which the slots extend, a draft key extending through the slots in the draft lugs, coupler and yoke for holding said coupler and yoke in operative relation, said draft 25 lugs being provided with abutment portions reinforced for engaging an associated follower on one side and furnishing shoulders of increased breadth to support said draft key on the other side, the slot in the coupler 30 being lengthened in accordance with the decrease in length of the slots in the yoke, and the slots in the draft lugs being shortened in accordance with the shortening of the yoke slots whereby a normal amount of 35 travel of the coupler is permitted.

7. In a railway draft rigging, in combination with draft sills, of slotted draft lugs connected thereto, said draft lugs being provided with follower engaging abutments adjacent corresponding ends of said slots, said 40 slots being materially shortened at the abutment ends of the draft lugs with the metal in said abutments continued for substantially the full width thereof to the adjacent ends of said slots, whereby the span between the adjacent ends of said abutments is materially 45 shortened, a slotted coupler, a slotted yoke, and a draft key extending through the slots in the draft lugs and adapted for transmitting buffing force to the inner ends of the slotted portions in the draft lugs and also extending through the slots in the coupler and yoke for holding the same in operative position, the slot in the coupler being increased 50 in length to correspond with the decrease in length of the draft lug slots, whereby a normal amount of coupler travel is permitted.

8. In a railway draft rigging, in combination with draft sills, of slotted draft 60 lugs connected to the interior faces thereof and provided with front follower abutments extending toward each other, the slots in said lugs being materially decreased in length from the follower abutment end of the lugs 65 with the provision of an increased amount

of reinforcement strengthening said follower abutments for substantially the full width thereof, whereby the span between the adjacent portions of the inner ends of the draft key slots is materially decreased, a slotted 70 coupler, a slotted yoke, a draft key extending through the slots in said draft lugs adapted for transmitting force to the inner ends of said slotted portions adjacent the reinforced follower abutments, said key being 75 adapted to transmit a materially greater amount of force because of the decreased span provided, said key also extending through the slots in the coupler and yoke for holding the same in operative relation 80 with respect to the draft lugs, the slot in the coupler being lengthened to correspond with the decrease in length of the draft lug slots, and the slots in the yoke being abnormally short to correspond with the shortened draft 85 lug slots, whereby the key travels less than the coupler on motion of said coupler in one direction.

9. In a railway draft rigging, in combination with draft sills, of slotted draft lugs connected thereto, said lugs having abutment portions adapted for engagement with a cooperating front follower member, said abutment portions being reinforced by discontinuing the slots at a greater distance than normal from said abutment portions to leave a larger amount of metal therein, a slotted coupler, a slotted yoke, a draft key extending through the slots in draft lugs, 90 coupler and yoke for operatively supporting said coupler and yoke, the metal in said abutment portions adjacent the rear ends of the slots therein serving to provide increased bearing area for the key, the construction of the coupler and key being such that a 95 normal amount of coupler travel is permitted.

10. In a railway draft rigging, in combination with draft sills, of slotted draft lugs connected thereto, said draft lugs being provided with follower engaging abutments adjacent corresponding ends of said slots, said slots being materially shortened at the abutment ends of the draft lugs with the metal in said abutments continued for substantially the full width thereof to the adjacent ends of said slots, whereby the span between the adjacent ends of said abutments is materially shortened, a slotted coupler, a slotted 110 yoke, and a draft key extending through the slots in the draft lugs and adapted for transmitting buffing force to the inner ends of the slotted portions in the draft lugs and also extending through the slots in the coupler and yoke for holding the same in operative 115 position.

11. A draft lug adapted for application to a railway car sill comprising a portion engageable in a cooperating slot in said sill, an abutment portion extending inwardly 120

from said lug for engaging an associated front follower, said lug being provided with a substantially longitudinal slot therein discontinued short of the abutment portion, said 5 abutment portion adjacent the near end of the slot being reinforced by increasing the thickness of the metal therein and extending said thickened metal for substantially the full width of said abutment thereby providing increased bearing area for an associated 10 draft key.

In testimony whereof I affix my signature.
